PRINTING POINT INDICATOR

Lyle A. Dunstan, Portland, Oreg.

Application January 9, 1942, Serial No. 426,231

1 Claim. (Cl. 88—24)

This invention relates to a printing point indicator which is designed to provide a light image that is directed at a printing point for the purposes of indicating visually such printing points.

My invention is particularly adapted for use in a typewriter having a fixed printing point. Often it is desired by an operator of such a machine to have the printing point delineated for the purposes of making corrections to typewritten work, for making insertions in a work sheet introduced in such a machine, and for many other useful purposes.

It will be understood, of course, that the use of my invention is not restricted to typewriters and that it is my specific intention to avoid such a limitation in the concept of the use of my invention. I shall describe my invention as though used with a typewriter because such a mechanism presents problems that are met and solved by my invention.

It often occurs in typewriting that corrections be made in the work being done or that insertions be made at a specific point upon the work sheet. The bounds of the printing point are not customarily delineated in such a typewriter except within the judgment of the operator, and when it is necessary to print a character within a specific space, unless the operator exercises the highest degree of skill, it is not always possible to place such character at the desired point.

It is an important object of my invention to place, at a printing point, a light image delineating that point.

Another object of my invention is to provide means for placing a light image at a printing point and adapted to focus that light image to clearly delineate said space.

Another object of my invention relates to the provision of a printing point indicator which is enclosed in a unitary housing and adapted for ready attachment to any suitable mounting means for use, and in which the operating elements are entirely contained.

A further object of the invention is the provision of a housing having an internal light source for providing a beam of light, said housing also having means for impressing an image upon the beam of light and means for bending the beam of light to direct it in a desired manner.

Still another object of my invention relates to the provision in a printing point indicator that is enclosed in a housing, including means for focusing a light image pressed upon a beam of light to clearly define or delineate a printing point.

More specifically, my invention lies in the pro-

vision of a housing having a light source capable of producing a beam of light in said housing and means for impressing an image on said beam of light, said printing point indicator being adapted to focus such an image and to align it properly with relation to the printing point for the purposes of clearly defining that printing point.

Other objects and advantages of the invention will be more apparent during the course of a 10 reading of the following specification. It will be understood that the showing of my invention in the accompanying drawing and the following description is for the purpose of exemplifying the invention, and that changes and alterations in 15 the general arrangement of parts may be made within the scope of the subjoined claim.

Referring to the drawing,

Figure 1 is a schematic showing of my printing point indicator as associated with typewriting 20 mechanism and useful for indicating the printing point thereof,

Figure 2 is a longitudinal sectional view through one form of my printing point indicator, 25 Figure 3 illustrates means for bending a beam of light, having a light image impressed thereon, and means for adjusting said bending moment,

Figure 4 is a cross-sectional view taken along line 4—4 of Figure 2, illustrating in face view 30 means for impressing an image upon a light beam, and

Figure 5 is a modified form of my printing point indicator, designed and adapted for specific installation.

Throughout the drawing like reference numerals are employed to indicate like parts. The numeral 10 designates a writing or printing machine platen having end operating handles 11 and 12. It is understood that such a platen is axially rotated and that sheet material is presented to the printing point of such a machine by axial indexed rotation of the platen. It is customary for an inked ribbon 14, fed from spools such as 15 and 16, to be conveyed or led to the printing point of the machine as indicated by the numeral 17. The printing members of such a machine will strike the inked ribbon and produce an impression upon the sheet material presented by the platen at a fixed printing point in the machine.

For indicating and delineating this printing point, I employ a light source 20 to which current may be supplied by means of a cord 21. A beam of light 22 emanating from that source passes through object means such as disc 23 and an

image of the nature shown in Figure 4 is impressed upon that light beam. To facilitate and even the light beam a diffusing disk is indicated at 24.

The numeral 25 designates a lens system in the path of the light beam and the light bending means 26, which may or may not be employed depending upon the manner in which my printing point indicator, is mounted in the path of the beam.

These elements are enclosed within a housing 27 having a side aperture 28, so that the light image carried by the beam may be directed at the printing point of a mechanism such as a typewriter in which is an ideal point of use of my invention.

Referring now to Figure 2, I show an open-ended cylindrical housing 30 having a side aperture 31. In one end of the housing a cup 32 is provided with the means 20 serving as a light source. As is shown in Figure 2, the diffusing member 24 and the object disc 23 are mounted in the open end of the cup. It will be apparent that the cup is adapted for longitudinal and axial movement with relation to the housing 30 for a purpose later to be described.

A second cup 34 having a side aperture 35 adapted to register with the aperture 31 of the housing, is also longitudinally and axially movable in the other end of the housing. The light bending means 26 is mounted in cup 34 as is also the lens system 25.

It will be seen that the device of Figure 2 may have the housing mounted in any suitable point on a typewriting machine, and for the purposes of adjustment, cups 32 and 34 may be moved toward or away from each other, and also rotated axially of the housing to align a light image at a desired point as well as to focus that image.

Under certain circumstances, it has been found advisable to provide means for altering the angle of bend imparted to the image carrying light beam. In such an instance a cup 40 has the light bending member 26 mounted therein on a spring blade 41 and a screw 42, having a hand knob 43, presses against the blade 41 and will serve to change the angle of the reflector member 26.

In the showing of Figure 5 the housing 50 has open ends that are disposed at an angle to each other, preferably in a right angular manner. The reflector member 51 is positioned at the approximate point of joinder of the axis of the two legs of the housing. In one leg of the housing the lens system 52 is mounted and in the other leg of the housing image producing member 53 and the diffusing member 54 may be mounted. A cup 55 adapted by means of a pivot bolt 56 for joinder to a suitable mount encircled by a hoop 57 and contains the light source means 58. The housing 50 is mounted on the member 55 for swiveling movement to change the direction of the light means emanating therefrom.

In certain forms of the invention it is desirable to employ a light bulb of relatively low wattage or low voltage or both. When the device is to be energized from a conventional 110-volt line, it is possible to reduce the voltage by using a line resistance 60 on one of the leads. A switch is also shown at 62 to permit the light being ignited at the will of the operator.

An extremely convenient feature of the devices of the drawing, other than as printing point indicators, is the provision of supplemental illumination for a typist where it is desired to increase visibility of the printed characters as they are made upon the paper.

I claim:

A printing point indicator comprising a cylindrical housing having a side aperture, a cup in one end of said housing adapted to be moved in longitudinal and axial relation thereto, a light source carried by said cup for providing a beam of light in said housing, means associated with said cup for impressing an image upon such a beam of light, a second cup in the other end of said housing adapted to be moved in longitudinal and axial relation in said housing and provided with means for bending said light beam to direct it out the side aperture of the housing, and means for focusing said light image.

LYLE A. DUNSTAN.
